UNITED STATES PATENT OFFICE

EDGAR B. SYMONS, OF LOS ANGELES, CALIFORNIA, ASSIGNOR TO NORDBERG MANUFACTURING COMPANY, OF MILWAUKEE, WISCONSIN, A CORPORATION OF WISCONSIN

CRUSHING APPARATUS

Original application filed September 19, 1927, Serial No. 220,471. Divided and this application filed January 9, 1930. Serial No. 419,566.

My invention relates to improvements in gyratory crushing machines of the type in which the material to be crushed is fed or allowed to flow by gravity through a crushing zone between a normally fixed concave and a cone within the concave. One object of my invention is to provide a new and improved type of gyratory crusher adapted for fine crushing. Another object is to provide such a crusher wherein means are provided to permit a very fine adjustment of the cone and concave. Another object is to provide adjusting means whereby the adjustment may be quickly and closely effected without stoppage of the crushing operation.

The present application is a division of my copending application No. 220,471, filed September 19, 1927.

Other objects will appear from time to time in the course of the specification and claims.

I illustrate my invention more or less diagrammatically in the accompanying drawings, wherein—

25 Figure 1 is a top plan view;

Figure 2 is a section along the line 2—2 of Figure 1;

Figure 3 is a section along the line 3—3 of Figure 2;

30 Figure 4 is a detail.

Like parts are indicated by like symbols throughout the specification and drawings.

A is a bed or support upon which rests a frame A¹ provided at its base with a horizontal reinforcing flange A² and strengthened by the reinforcing flanges or ribs A³. Projecting inwardly from the frame A¹ are the radial flanges or ribs or frame members A⁴, which join and support a central cylindrical housing B.

The housing or cylinder B is outwardly expanded adjacent its upper end as at B¹. A suitable bronze bearing member or sleeve B² penetrates the cylinder. The cylinder B is provided with a plurality of vertical channels B³ which are penetrated by corresponding ribs B⁴ formed on the exterior of the sleeve B. These serve to prevent the rotation of the sleeve B² in relation to the cylinder B.

50 The sleeve is loosely fitted to the cylinder at

the upper part, the intervening space being filled for example with the Babbitt metal B⁵.

The bottom of the cylinder is closed, for example by the cap C which may be bolted as at C¹ and which supports the lower bearing plate C² upon which is positioned the ball race member C³ with the bearing balls C⁴ which supports the plate C⁵, peripherally beveled as at C⁶ and centrally apertured as at C⁷.

D is an eccentrically apertured sleeve resting on and in general conforming to the upper surface of the plate C⁵. It is provided at its upper end with the outwardly projecting ring gear D¹ enclosed within the space defined by the wall or housing B¹ and projecting outwardly and downwardly about the upper edge of the housing or cylinder B. It is provided at one point of its periphery with the upwardly hollow enlargement D², adapted to receive a variable quantity of lead or other heavy material D³, adapted to serve as a counterweight.

The sleeve D is eccentrically apertured from top to bottom, the aperture D⁴ being downwardly tapered from top to bottom of the sleeve. D⁵ is a wear taking or bearing member of any suitable anti-friction material. The member D⁶ is transversely grooved or slotted from top to bottom as at D⁶ and is penetrated by apertures D⁷ in communication with apertures D⁸ in the thin wall of the eccentric sleeve D.

The sleeve of the housing B is at one side provided with the outwardly projecting shaft housing E, herein shown as integral with it. Mounted therewithin is the shaft supporting sleeve E¹, bolted to the main frame, for example as at E². The sleeve E¹ is provided at each end with the anti-frictional bearings or bushings E³. Mounted in said bearings is the drive shaft E⁴, to the inner end of which is keyed the bevel pinion E⁵ in mesh with the gear D¹. E⁶ are oil grooves or passages. The outer bushing E³ is contacted by the ring E⁹, of angular cross-section, which in turn is surrounded by the plate or housing E¹⁰, in bearing engagement therewith, bolted to the outer end of the sleeve E¹. E¹¹ is a pulley keyed to the

shaft E⁴. The top of the housing B is closed by the cover plate H which is formed or provided with the spherical bearing surface H¹, which may be, if necessary, of any suitable anti-frictional material. Surrounding the bearing portion H¹ is the circumferential well or sump H² in the bottom of which are the oil discharge passages H³ which provide free drainage into the interior of the housing member B¹. Beyond the sump is positioned the upwardly projecting circumferential flange H⁴ which is provided with a spherical bearing surface H⁵ concentric with the main spherical bearing surface H¹.

15 Mounted in the eccentric D is the tapered shaft J, which includes the downwardly tapered portion J¹ and the upwardly tapered portion J². The shaft is further provided with an upper reduced cylindrical portion J³ and a screw threaded portion J⁴ thereabove and is transversely slotted at its top as at M¹². The shaft is further axially apertured as at J⁶ with the transverse upper passage J⁷ extending therefrom to the outside of the shaft adjacent its top.

20 L is a crushing cone seated upon the tapered portion J² of the shaft. The lower central portion of the cone is spherically formed and is herein shown as provided with a bronze spherical liner L¹ having a circumferential upwardly turned flange L² seated in a circumferential groove L³ in the cone. It will be understood that the liner L¹ conforms to the spherical bearing surface H¹. Formed in the spherical lower face of the cone is a circumferential oil duct L⁵ which is in communication, through the passage L⁶, with the oil duct J⁶ in the shaft J. Formed in the liner L¹, aligned beneath the duct L⁵, are a plurality of oiling openings L⁷, herein shown as having downwardly and outwardly flared walls.

25 L⁸ is a downwardly depending flange formed in the bottom of the cone, beyond the central spherical portion. Surrounding it is the circumferential groove L⁹ in which is positioned the upwardly projecting flange L¹⁰ upon the ring L¹¹. It will be understood that the lower surface of the ring L¹¹ is spherical, and conforms to the spherical surface H⁵ of the opposed flange H⁴. L¹² is any suitable packing, which may be of felt.

30 The cone depends outwardly beyond the structure above described, as at L¹⁵ and terminates in a downwardly turned curtain or apron L¹⁶.

35 The frame member A¹ is provided about its upper edge with an outwardly projecting flange P provided with the opposed beveled faces P¹ and P². Seated upon the flange is a ring P³ generally conforming to said faces. P⁴ indicates a ring of channel iron outwardly surrounding the housing or frame member A¹. Passing through it and through the flange P and the member P³ are a plurality of secur-

ing bolts or pins P⁵ upwardly headed as at P⁶ and provided with adjusting and lock nuts P⁷ beneath the channel ring P⁴. P⁸ indicate spiral compression springs coiled about said pins P⁵. It will be understood that the springs P⁸ are compressed between the flange P and the ring P⁴ and thereby exert, through the nuts P⁷ and the bolts P⁵ a downward compression against the ring P³, whereby it is held normally locked against the flange P.

170 The ring P³ is screw threaded as at P¹⁰ to conform to the opposed screw threaded member Q¹ on the concave supporting element Q.

180 Integral with the member P³ are outwardly and upwardly projecting lugs T having a smaller outward lug T¹. Each lug T is apertured to receive a shaft T², to which is secured the ratchet wheel T³ and the lower portion T⁴ of the ratchet clutch T⁵. T⁶ is a dog pivotally mounted to the lug T¹ and held in engagement with the ratchet wheel T³ by the spring T¹⁰.

190 Integral with the member Q¹² and extending outwardly, is a circular flange T¹⁴ which is provided with a plurality of apertures T¹⁵ adapted to receive upwardly projecting pins T¹⁶, which may engage the ring T¹⁷ of the chain T¹⁸, the chain being wound around and securely fastened to the shaft T² as shown in Figure 2. I find it desirable, in large cone crushers, to employ means for permitting or obtaining fine adjustment of the opposed screw threaded members or an accurate rotation of the member Q¹ in relation to the opposed screw threaded member P³, to permit an accurate positioning of the locking means employed.

200 W indicates a lug vertically apertured as at W¹, the lug projecting outwardly from the member P⁸. Two of such lugs project therefrom at diametrically opposed points. W²

210 indicates a pin seating in the aperture W¹ and connected to or formed integrally with a horizontal cylinder W³. Mounted in the cylinder is the screw W⁴ with an inner flange W⁵ abutting against the end W⁶ of the cylinder W³. The end W⁶ is apertured as at W⁷, to receive the cylindrical extension W⁸ of the screw W⁴. It in turn is externally 220 screw threaded as at W⁹ to receive a head W¹⁰ which is locked thereupon and which is keyed thereto and which is provided with the handle W¹¹, whereby the screw W⁴ may be rotated. W¹² indicates a second cylindrical sleeve adapted to penetrate the opposite end of the sleeve W³. The penetrating end is screwthreaded as at W¹² for engagement with the screw W⁴. Its opposite end is provided with the adjacent lugs W¹⁴. The ends of said lugs are joined by the plate W¹⁵ which is pivoted as at W¹⁶ to one flange and is slotted as at W¹⁷ to engage the bolt W¹⁸ upon the other lug.

The use and operation of my device are as follows:

I illustrate a cone crusher of the general type shown for example in my Patent No. 1,592,813. In a crusher of this type, the adjustment of the closest approach of cone and concave becomes extremely important. Since the material discharged is sized by such closest approach, a practically uniform sizing is obtained. However the size of product desired shifts from time to time, for example, in gravel pit work and it becomes desirable to obtain a quick adjustment of the device. I provide means for adjusting it without interrupting the operation of the machine. The concave Q carries a screw threaded upwardly projecting member Q^1 which is in engagement with the opposed screw threaded portion P^{10} of a holding member P^3 which normally rests on the upper edge of the frame A^1 . In order to effect a withdrawal of the concave from the cone I impart a rotary movement to the concave in relation to such holding member. I illustrate adjusting means, namely, for rotating the concave through the rotation of the vertically axised drum or drums T^2 . As the drum is rotated it winds in any suitable flexible member, for example, the chain T^{18} , the terminal eyelet T^{17} which engages one of the pins T^{16} . Thus in response to rotation of the drum T^2 , the concave is positively rotated and its screw threaded relation with its holding member moves it toward or away from the cone. Obviously the direction of rotation may be controlled at will, depending on the point at which the pin T^{16} is dropped or positioned in one of the apertures T^{15} to which the eyelet T^{17} is attached.

In order to prevent relative rotation of concave and holding member when adjustment is not desired, I may employ the screws Q^{16} . Tightening of the screws will securely lock the threaded members P^3 and Q^1 .

It will be understood that when P^3 and Q^1 are locked together or held against rotary movement that they act as one member. The number and strength of the springs P^8 is normally such as to hold the concave in fixed relation to the cone. In case of abnormal crushing stresses, or when uncrushable material passes through the crushing zone, the springs serve as a release means and permit the concave and its supporting member to tilt upwardly away from the cone. In order to obtain any desired adjustment I may employ for example the tensional members or chains T^{18} each of which is provided with a loop T^{17} which may be put upon any desired pin T^{16} which pin may be dropped into any of the holes T^{15} positioned about the flange T^{14} . The opposite end of each chain T^{18} is secured upon the drum T^2 , which drum may be rotated as by the lever T^6 which has an overrunning connection

therewith, including the member T^4 . The ratchet teeth T^3 in connection with the dog T^6 prevent undesired retrograde movement of the drum. Thus the operator may rotate the member Q^1 in relation to the member P^3 . It will be understood that the member Q^{12} , associated with the flange T^{14} , in which the pins T^{16} are mounted, moves in unison with the member Q^1 and causes its rotation, as through the screw Q^{16} as shown in Figure 2. In the larger size of cone crushers this tensional adjusting means is effective to impart relative movement to the opposed screw-threaded members P^3 and Q^1 , but is insufficiently accurate to provide for an exact adjustment. In order to maintain the members P^3 and Q^1 against relative movement when adjusted I provide the telescopic locking structure above discussed, which includes the members W^3 and W^{12} and the screw W^4 actuated by the crank W^{11} . At the end of the member W^{12} is a jaw which includes the opposite jaw members W^{14} and the transverse connecting piece W^{15} . The details of this structure are shown in Figure 4. When the member Q^1 has been moved to the desired point of adjustment, preferably with one of the holes T^{15} in general alignment with the end of one of the members W^{12} , the member W^{12} may be moved, by rotation of the crank handle W^{11} , until the jaw is aligned with an aperture T^{15} . Thereupon one of the pins T^{16} may be dropped through the jaw W^{14} to penetrate said aperture T^{15} , thus preventing further relative movement of the member Q^1 in relation to the member P^3 .

I have illustrated, as in Figure 1, two of the said adjustable locking connections, but it will be realized that the number may be varied to suit the size and duty of the machine with which the locking device is employed. Furthermore, it will be understood that I may, by varying the size of the telescopic structure, increase its strength and employ it to impart adjusting rotation, if necessary, of the bowl in relation to the frame.

I claim:

1. In a gyratory crusher, a frame, a crushing cone and means for gyrating it, a concave surrounding said cone and means for adjusting said concave, said means including opposed screw threaded members associated with the concave and the crusher frame, and means for imparting relative rotary movement to said opposed screw threaded members, including a tubular member and means for securing it in relation to the concave, a second tubular member in telescopic relation with the first, and means for securing it in relation to the crusher frame and means for imparting relative axial movement to the two tubular members.

2. In a gyratory crusher, a frame, a crushing cone and means for gyrating it, a

- concave surrounding said cone and means for adjusting said concave, said means including opposed screw threaded members associated with the concave and the crusher frame, and means for imparting relative rotary movement to said opposed screw threaded members, including a tubular member and means for securing it in relation to the concave, a second tubular member in telescopic relation with the first, and means for imparting relative axial movement to the two cylindrical members, including a screw held against movement in relation to one of said tubular members and in screw threaded relation with the other, and means for rotating it.
3. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members against rotation in relation to each other, at any desired relative position of the opposed screwthreaded members, including a pair of relatively rotatable members in screwthreaded relation, means for securing one of said members in relation to the concave and the other in relation to the crusher frame, and means for imparting relative rotation to said rotatable screwthreaded members.
4. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members against rotation in relation to each other, at any desired relative position of the opposed screwthreaded members, including a pair of relatively rotatable members in screwthreaded relation, means for securing one of said members in relation to the concave and the other in relation to the crusher frame, and means for imparting relative rotation to said rotatable screwthreaded members, including a manual crank associated with one of said members.
5. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members

against rotation in relation to each other, at any desired relative position of the opposed screwthreaded members, said adjustable securing means including a plurality of telescopic members, one mounted upon the frame and the other secured in relation to the bowl, and means for imparting relative longitudinal movement to said telescopic members.

6. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members against rotation in relation to each other, at any desired relative position of the opposed screwthreaded members, said adjustable securing means including a plurality of telescopic members, one mounted upon the frame and the other secured in relation to the bowl, and means for imparting relative longitudinal movement to said telescopic members, said first mentioned telescopic member being pivotally mounted in relation to the frame.

7. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members against rotation in relation to each other, at any desired relative position of the opposed screwthreaded members, including a telescopic member mounted upon the frame and adapted for locking engagement with the bowl, and means for varying the effective length of said telescopic member.

8. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members against rotation in relation to each other, at any desired relative position of the opposed screwthreaded members, said securing means including a telescopic member mounted upon the frame, said member including a portion adapted to be aligned with an opposed portion of the bowl, and a locking member adapted to be interposed between said telescopic member and the bowl.

9. In a gyratory crusher, a frame, a crushing cone and means for gyrating it, a bowl surrounding said cone and means for adjusting said bowl in relation to said frame, said means including opposed screwthreaded members associated with bowl and frame, means for imparting relative rotary movement to said opposed screwthreaded members, and adjustable securing means adapted to secure said screwthreaded members against rotation in relation to each other, at any desired relative position of the opposed screwthreaded members, said securing means including a telescopic member mounted upon the frame, said member including a portion adapted to be aligned with an opposed portion of the bowl, and a locking pin adapted to penetrate a portion of said telescopic member, and an aligned aperture upon the bowl, the bowl being provided with a plurality of such apertures spaced about the periphery thereof.
10. In a gyratory crusher, a frame, a crushing cone and means for gyrating it, a bowl surrounding said cone and means for adjusting said bowl in relation to said frame, said means including opposed screwthreaded members associated with bowl and frame, and means for imparting relative rotary movement to said opposed screwthreaded members, and for locking them in position when adjusted, including a telescopically extensible member mounted upon the frame, and a securing connection between said member and the bowl, one unit of said telescopically extensible member being mounted on the frame and the other being adapted to be secured to the bowl, and means for imparting relative longitudinal movement to said units.
11. In a gyratory crusher, a frame, a crushing cone and means for gyrating it, a bowl surrounding said cone and means for adjusting said bowl in relation to said frame, said means including opposed screwthreaded members associated with bowl and frame, and means for imparting relative rotary movement to said opposed screwthreaded members, and for locking them in position when adjusted, including a longitudinally extensible member mounted upon the frame, and a securing connection between said member and the bowl, the longitudinally extensible member being adapted to receive a locking pin, the bowl being apertured to receive said pin.
12. In a gyratory crusher, a frame, a crushing cone and means for gyrating it, a concave surrounding said cone and means for adjusting said concave, said means including opposed screwthreaded members associated with the concave and the crushing frame, and means for imparting relatively rotary movement to said opposed screwthreaded members, including a longitudinally extensible member, one end of which
- may be secured to the concave and the other to the frame, and means for longitudinally extending and retracting said member, said member including a plurality of telescopic elements, and means for securing one of said elements to the concave and the other to the frame.
13. In a gyratory crusher, a frame, a crushing cone and means for gyrating it, a concave surrounding said cone and means for adjusting said concave, said means including opposed screwthreaded members associated with the concave and the crushing frame, and means for imparting relatively rotary movement to said opposed screwthreaded members, including a longitudinally extensible member, one end of which may be secured to the concave and the other to the frame, and means for longitudinally extending and retracting said member, said extensible member including an element pivotally secured to the frame and an additional element longitudinally movable in relation thereto, said last mentioned element having a fork on one end thereof and a closure for the fork, the concave being provided with an upstanding element adapted to penetrate between the arms of the fork, the closure for the end of the fork being adapted to prevent relative lateral movement of the extensible element and said upstanding element.
